INTAKE TYPE UNLOADER FOR COMPRES-
SORS AND THE LIKEWilliam P. Dalrymple, Rochester, N. Y., assignor
to American Brake Shoe Company, Wilmington,
Del., a corporation of Delaware

Application November 2, 1945, Serial No. 626,228

7 Claims. (Cl. 137—153)

1 This invention relates to automatic unloaders and particularly to what are known as intake type of unloaders for use in connection with air compressors and the like. Unloaders of the aforesaid character are controlled by the pressure variations in the pressure tank so that the intake of the compressor is closed when the tank pressure reaches a selected maximum, thereby to stop further supply of compressed air to the tank while at the same time removing or reducing the load on the compressor, and when the tank pressure has been reduced in a predetermined amount by use of air therefrom, the intake of the compressor is opened and the compression of air is again resumed.

Various means have been employed to close the intake of compressors for unloading purposes, and such means have usually been in the form of complicated piston valve and needle valve mechanism operating under pressure from the compression tank. Since the efficiency of the unloader depends to a large extent upon the degree of perfection of construction and interrelation of the parts, the cost thereof has been comparatively excessive, while maximum efficiency has been difficult to attain. To reduce the cost of construction and increase the efficiency of operation of unloaders of the aforesaid character are the primary objects of the present invention, and an object related thereto is to simplify the construction of intake type unloaders by completely eliminating the use of piston and needle valves.

Heretofore, intake type unloaders employing piston and needle valves have necessarily been limited to effective operation over only a relatively narrow range of pressure variations, since the areas acted upon by the pressure has been relatively limited. It is, therefore, another object of the present invention to materially increase the range of pressure variations over which effective operation of automatic pressure unloaders may be employed. An object related to the foregoing is to provide a greatly increased area upon which the main working pressure may act, and more specifically to afford such area by a diaphragm of relatively large diameter.

In the unloading of compressors it is generally desirable to start their operation almost instantaneously upon the attainment of the predetermined pressure in the tank, since any appreciable lag might prove dangerous or otherwise undesirable. Accordingly it is still a further object

2 of this invention to afford an unloader that is highly sensitive and capable of instantaneous response to predetermined tank pressures, and objects ancillary to the foregoing are to provide a pair of diaphragms, one responsive to the pressure in the tank and adapted to open a pilot valve to a main working chamber having a relatively larger diaphragm which by reason of its larger working area responds readily to small pressure variations to close the air intake of the compressor.

Yet another object of this invention is to afford a diaphragm actuated automatic pressure unloader wherein the sequence of operations is so timed and arranged as to afford greatly increased efficiency and speed in unloading. Objects relating to the foregoing are to prevent the exhaust or waste of air to atmosphere from the working chamber of the main diaphragm during the time that air is being admitted thereto for the purpose of operating the main diaphragm and the associated unloading valve.

Still another object is to provide an improved diaphragm operated unloader which is so arranged that the flexible diaphragms may easily be replaced when necessary.

Yet further objects are to afford an automatic unloader having a minimum number of working parts so as to decrease the frequency of replacements and increase the durability and over-all life of the apparatus, while at the same time eliminating expensive close-tolerance machining operations and reducing the over-all cost of construction.

Other and further objects of the present invention will be apparent from the following description and claims, and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a partially diagrammatic elevational view of a compressor system including a tank and compressor shown partially in section and equipped with the automatic intake unloader of the present invention;

Fig. 2 is an enlarged cross-sectional view of the unloader in its open position;

Fig. 3 is a top plan view of the apparatus; Fig. 4 is a cross sectional view of the apparatus in its unloading position wherein the pilot valve is open and the main unloading valve is closed;

Fig. 5 is a similar cross sectional view showing the apparatus at substantially the end of an unloading cycle when the pressure controlled pilot valve has been closed and the main unloading valve is about to start from its closed position to its open position;

Fig. 6 is an enlarged sectional view of the pilot valve and diaphragm mechanism of another embodiment of the invention;

Fig. 7 is a similar cross sectional view showing the parts in an intermediate relationship assumed during the opening and closing movements of the pilot valve; and

Fig. 8 shows the pilot valve in its fully open position.

For the purpose of disclosure the invention has been herein illustrated in Figs. 1 to 5 as embodied in an unloader 10 and is shown in Fig. 1 in position on the intake 11 of a compressor C. The compressor C is shown as a part of a compressor system which includes a pressure tank T that is charged by the compressor through a discharge line 11A. The compressor C has a piston 12 that is reciprocable in a cylinder 13 by conventional means including a crank shaft 14 and a piston rod 15, and conventional inlet and outlet valves 17 and 18 are afforded for controlling the passage of air from the inlet 11 and through the cylinder 13 to the tank T.

The unloader 10 is in the nature of an automatic valve, as will hereinafter be fully described, and may be closed so as to close the intake 11 of the compressor or may be opened so as to permit normal flow of air into the intake 11 of the compressor. Such operation of the unloader is under control of the pressure in the tank T, and for this purpose, a control pipe or connection 20 is extended from the tank to the unloader 10.

The specific construction of the unloader of the present invention is disclosed in Figs. 2 to 5 of the drawings, wherein it will be observed that the unloader has a main body 25 in the nature of an L-valve body that affords tubular arms 25A and 25B disposed at right angles to each other and having threaded axial openings 26A and 26B formed therein so as to open into the hollow interior of the valve body 25. Inwardly of the opening 26B, the valve body 25 has a sleeve-like extension 27 that defines a valve orifice 28 having a flat valve seat 29 surrounding the upper end of the orifice 28, and this valve orifice 28 opens into a chamber 30 formed within the valve body 25 so as to communicate with the opening 26A. The openings 26A and 26B are disposed at right angles to each other so that fluids such as air may pass through the valve body, and such flow of fluid through the valve body is controlled by a disc-like valve member 31 disposed within the chamber 30 and having a resilient surface arranged to seat against the valve seat 29 so as to close the valve opening 28. The valve member 31 is carried on a valve stem 32 that is reciprocable in a bearing sleeve 33 so that the valve member 31 may be moved from the closed position of Fig. 4 to the open position of Fig. 2.

The bearing sleeve 33 is in the present case formed in an axial relation on a spring supporting plate 34 that is carried on an upwardly facing shoulder 35 formed at the lower end of an axial opening 36, the opening 36 being formed

in the valve body in alignment with the opening 26B and the valve opening 28. The upper end of the valve stem 32 extends beyond the bearing sleeve 33 and means including a spring 37 are associated with the extended upper end of the valve stem 32 for controlling the position of the valve 31.

In accordance with the present invention, the valve operating means are afforded by a flexible main diaphragm 40 that is rested about its outer edges upon a mounting flange 41 that is extended outwardly about the upper end of the opening 36. The peripheral edge of the diaphragm is clamped against the flange 41 by a mounting plate 42 the edge flange 42A of which bears against the border portion of the diaphragm 40. The mounting plate 42 is held in place by a plurality of cap screws 43, Fig. 3, so that the mounting plate 42 may be readily removed for inspection or replacement of the diaphragm 40. The valve body 25 is tapered downwardly as at 44 about the border portion of the opening 36 so that the diaphragm 40 may be bent downwardly to the position shown in Fig. 4, while the lower surface of the mounting plate 42 is recessed upwardly as at 45 so as to define a pressure chamber 46, Fig. 4, and the diaphragm 40 may be bent upwardly against the surface 45 as viewed in Fig. 2 in order to permit opening movement of the valve 31. Such upward flexing of the diaphragm 40 is attained by the coiled spring 37 which bears at its lower end on the plate 34 and at its upper end on a disc 47 that bears against the lower face of the diaphragm 40. The disc 47 has a downwardly facing central hub 47A formed thereon that embraces a tapered upper end 32A on the valve stem 32, thereby to aid in locating these two parts with respect to each other, and the disc 47 and the stem 32 are caused to move as a unit by welding the hub 47A to the surface 32A.

The mounting plate 42 has a pressure inlet port 48 formed centrally thereof so that the pressure fluid may be supplied to the pressure chamber 46 for the purpose of forcing the diaphragm 40 from its upwardly extended position of Fig. 2 to the downwardly extended position of Fig. 4, thereby to close the valve 31, and when the valve 31 is to be closed for the purpose of unloading the compressor, the necessary pressure fluid is admitted to the pressure chamber 46 through the valve opening 48 under the control of valve means that are associated with the valve opening 48.

Such valve means that are associated with the port or valve opening 48 are in the nature of a pilot valve and are arranged for operation by diaphragm means that are mounted upon the upper face of the mounting plate 42. Thus the mounting plate 42 has an annular recess 50 formed in its upper surface so as to form an inner rim 51 about the valve opening 48, and the annular recess 50 also affords an upstanding outer rim 52 upon which a control diaphragm 55 of flexible construction is mounted. The inner rim 51 has a flat upper surface that affords a valve seat 56 against which a resilient valve member 57 may be seated, and the valve member 57 is carried on the lower face of the control diaphragm 55 in a manner that will be described in detail hereinafter.

The control diaphragm 55 is clamped in position about its outer edge by an inverted cup-like spring housing 58 that is flanged at 58A at its lower end, and clamping screws 59 are extended through spaced lugs 60 formed on the flange 58A so as to pass downwardly and engage

the mounting plate 42. Thus the border portions of the control diaphragm 55 are secured in position about the top of the rim 52 so that the annular recess 50 constitutes a control chamber. The control chamber 50 has a bore 62 extended radially therefrom and the outer end of the bore 62 has an enlarged tapped portion 63 to which the control pipe 20 is connected. The pressure from the tank T is thus applied to the control chamber 50 so as to tend to raise the diaphragm 55 to its upwardly bent position of Fig. 4, but this is resisted by an adjustable control spring 65 that is housed within the spring housing 58. The lower end of the spring 65 rests upon an annular guide or pressure plate 66 that is slideable vertically within a cylindrical guide surface 67, and the lower face of the plate 66 rests upon the upper face of the control diaphragm 55. The plate 66 is utilized in the present instance in affording a mounting for the valve 57 on the diaphragm 55 and for this purpose a mounting bolt 68 is passed through the valve 57 so that the head of the bolt is exposed on the lower face of the valve, the location being such that the head of the bolt 68 may freely enter the valve opening 48. The bolt extends through the diaphragm 55 and the plate 66 and a nut 68A is provided on the upper end of the bolt 68 so that the valve member 57 may readily be replaced when this is desirable. At its upper end the spring 65 has a pressure plate 70 rested thereon and the tension or force of the spring 65 may be adjusted by an adjusting screw 71 that is threaded downwardly through the upper end of the spring housing 58 so as to bear upon the pressure plate 70. The adjusting screw may be held in its adjusted position by a cap-like lock nut 72 that embraces the upper end of the screw so that the lock nut may be tightened downwardly against a shoulder 73 on the spring housing.

The spring 65 is adjusted so that when the desired maximum pressure is attained in the tank T, the pressure applied to the lower face of the control diaphragm 55 will be effective to force the diaphragm 55 toward its upwardly bent position of Fig. 4, and when this occurs, the valve 57 is lifted from its valve seat 56 so that air pressure from the tank T may pass through the chamber 50 and the valve opening 48 and into the main pressure or working chamber 46. Thus the valve 57 acts as a pilot valve that under the circumstances just described permits flow of pressure fluid into the main working chamber 46, and the diaphragm 40, being of relatively large diameter, immediately flexes in a downward direction to the position shown in Fig. 4, and this causes the valve 31 to be moved to its closed position wherein the intake 11 of the compressor C is closed. This of course serves to unload the compressor C, and since no further air is supplied to the cylinder 13 of the compressor, there is no further increase of pressure within the tank T.

When the control diaphragm 55 is in its upper position, the effective area thereof is somewhat greater than it was prior to the opening of the valve 57, for the lower face of the valve 57 now is exposed to the pressure within the control chamber 50, and hence the diaphragm 55 will remain in its upper position of Fig. 4 until such time as the pressure within the tank T has been reduced by normal use or leakage to a value that is somewhat below the value at which the valve 57 is opened, this differential may be controlled by suitable selection of the relative areas that are effective on the diaphragm 55 in the closed

and open positions thereof. When the pressure in the tank T reaches such a value that the valve 57 returns to its closed position, the supply of pressure fluid to the working chamber 46 is cut off, and the diaphragm 40 starts to return to its upper position of Fig. 1. In order that such return movement may take place, the air within the working chamber 46 must be dissipated, and in the form of the invention illustrated in Figs. 1 to 5, this dissipating action is caused by a relatively small relief port 75 that is formed as an axial bore in a plug 76 that is screwed downwardly through the plate 42 so that the relief port 75 communicates with the working chamber 46. The size of the relief port 75 is relatively small so that during the period when the pilot valve 57 is opened, the loss of pressure fluid through the port 75 is negligible, and with the relief port 75 so proportioned, the pressure within the working chamber 46 is dissipated quite rapidly after closure of the pilot valve 57. As the pressure within the working chamber 46 is dissipated, the diaphragm 40 is forced upwardly by the spring 37 to its position of Fig. 1 so as to cause opening of the valve 31. When the valve 31 is thus opened, the supply of air to the intake 11 of the compressor C is again resumed, and the compressing action of the compressor C at once commences to build up the pressure in the tank T toward the predetermined maximum value.

In some instances it may be desirable to avoid continuous venting of air from the working chamber 46 during the unloading periods, and in accordance with the present invention this venting with the consequent waste of pressure fluid may be avoided through the elimination of the vent 75 and through the provision of a vent valve that is opened and closed as an incident to the operation of the pilot valve. Such an embodiment of the invention is illustrated in Figs. 6, 7 and 8 of the drawings wherein the mounting plate that affords the main pressure or working chamber of the unloader is fragmentally illustrated at 42B, and the related or similar parts of the mechanism are identified by similar reference characters with the suffix "B." Thus the mounting plate 42B has a centrally located valve opening 48B that terminates in an upstanding rim that affords a valve seat 56B and this valve seat 56B is adapted to be engaged by an annular valve member 57B that is operated in accordance with the pressure in the tank T by a control diaphragm 55B. The plate 42B has an outwardly and upwardly extending annular portion 80 that terminates in a flange or rim 52B upon which the border portion of the control diaphragm 55B is seated, and the border portion of the diaphragm 55B is held in place by the flanged lower end of a spring housing 58B of substantially the same character as that shown in Figs. 1 to 5. The sloping annular portion 80 serves to afford an annular control chamber 50B disposed about the valve seat 56B, and a passage 62B with an enlarged screw threaded outer end 63B serves to enable the pressure connection 20 to be extended and connected to the control chamber 50B.

The diaphragm 55B is normally pressed downwardly by a control spring 65B that is adjustable at its upper end in the same manner as shown in Fig. 2, and the pressure of the spring 65B is applied to the diaphragm 55B by a pressure plate 66B. The pressure plate 66B differs considerably from that shown in the other embodiment of the invention, in that an upstanding annular wall 82 is provided centrally of the plate and this annu-

lar wall 82 is closed at its upper end by a top wall 83. The wall 82 and the wall 83 serve to afford an inverted cup-shaped member that opens downwardly, and the internal surface of the annular wall 82 is screw threaded so as to receive a clamping sleeve 85 whereby a flat bearing plate 86 is secured against the lower surface of the wall 83. The clamping sleeve 85 extends through a central opening in the diaphragm 55B, and a lower clamping plate 87 is threaded onto the sleeve 85 so as to clamp the inner border portion of the diaphragm 55B against the lower surface of the plate 66B. Thus the sleeve 85 moves up and down with the diaphragm 55B as it is flexed, and the sleeve 85 serves as a part of the mounting for the pilot valve 57B. Thus the pilot valve 57B has a flange 88 at its upper edge and this flange is disposed within the sleeve 85 and above an inturned annular flange 89 formed on the lower end of the sleeve 85. The pilot valve 57B is normally urged downwardly with respect to the sleeve 85 by a resilient means housed within the sleeve 85 and such means as herein shown are in the form of an expansive rubber sleeve 90 that bears at its upper end against the plate 86 and at its lower end against the upper face of the valve 57B. Thus the valve 57B may be moved upwardly or downwardly with relation to the sleeve 85 and this capability is utilized in affording a vent valve means that is opened and closed in timed relation to the movements of the control diaphragm 55B. To this end, the pilot valve 57B has a vent opening 91 formed axially therein and this vent opening terminates in a conical valve seat 92 disposed at the lower end of the vent opening. The valve seat 92 is adapted for cooperation with a complementary valve head 94 that is of conical form, and this valve head is formed at the lower end of a valve stem 95. This valve stem extends upwardly and through the horizontal wall 83 of the pressure plate 66B. At its screw threaded upper end, the valve stem 95 has a nut 96 threaded thereon so as to engage the upper surface of the wall 83, and thus the spacing of the valve head 94 with respect to the plate 83 may be adjustably determined. This adjusted relationship of the valve head 94 is such that when the resilient member 90 causes the valve member 57B to be moved to its most downward position, with the flange 88 in engagement with the flange 89, the valve seat 92 will be engaged with the valve head 94, thereby to close the vent opening 91. When however the diaphragm 55B is forced downwardly to the position shown in Fig. 7, the lower face of the pilot valve 57B engages the seat 92, and this of course shuts off the flow of pressure fluid from the control chamber 50B through the valve opening 48B. The continued downward movement of the diaphragm 55B thereafter serves merely to shift the valve head 94 downwardly with respect to the valve member 57B and the seat 92, thus to move the valve head 94 to the open relationship shown in Fig. 6. When this occurs, the pressure in the working chamber 46B is vented about the valve head 94 and through the vent opening 91.

When the pressure in the tank T again approaches the maximum value, the initial upward movement of the diaphragm 55B serves to move the valve head 94 upwardly from the open position shown in Fig. 6 to the closed position shown in Fig. 7, and this closed relationship of the valve head 94 is maintained as the upward movement of the diaphragm 55B is continued. Thus the vent opening 91 is maintained closed during the

time when the pressure fluid is applied through the valve opening 48B to the working chamber 46B. As the pilot valve 57B is moved from its open position of Fig. 8 toward the closed position of Fig. 7, the closed relationship of the vent port 91 is also maintained, and it is only after the pilot valve 57B has been closed that the vent port 91 is opened. Thus the arrangement provided in the embodiment of the invention shown in Figs. 6 to 8 conserves pressure fluid and insures efficient and effective operation of the unloader.

From the foregoing description it will be apparent that the present invention enables intake type unloaders to be embodied in a simple and effective structure wherein the parts may readily be assembled or disassembled for inspection or replacement. Moreover, this invention enables the valve operating movements to be attained through the use of diaphragms, thereby eliminating the use of pistons which have heretofore been found to be costly and otherwise objectionable. It will also be apparent that under the present invention, the pressure fluid may be conserved through the provision of a pilot valve and a vent valve that are operated in timed and interrelated relationship by the control diaphragm of the unloader.

Thus, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims:

I claim:

1. In an intake type unloader for compressors and the like, a valve body having a passage therethrough and affording a main valve opening defined in said passage, a valve member for cooperation with said main valve opening and mounted for movement between open and closed positions relative to said main valve opening, a main diaphragm operatively associated with said valve member for imparting valve closing movement thereto, means cooperating with said main diaphragm to afford a main pressure chamber having a pressure inlet opening, a pilot valve for said inlet opening, a control diaphragm operatively associated with said pilot valve for operating the same, means yieldingly urging said pilot valve toward closed position, means cooperating with said control diaphragm to afford a control chamber that communicates with said main chamber when said pilot valve is open, means for supplying control pressure to said control chamber, means affording a vent opening for venting pressure fluid from said main chamber, a vent valve for said vent opening, and means operable by said control diaphragm to open said vent valve when said pilot valve is closed, and close said vent valve when said pilot valve is open.

2. In an intake type unloader for compressors and the like, a valve body having a valve chamber and passage therethrough and affording a main valve opening defined within said chamber, a valve member for cooperation with said main valve opening and mounted for reciprocating movement between open and closed positions relative to said main valve opening, a main diaphragm mounted exteriorly of said body in a plane at right angles to the reciprocating path of said main valve member and operatively associated with said valve member for imparting valve closing movement thereto, a mounting plate fixed

on said body and cooperating with said main diaphragm to afford a main pressure chamber having a pressure inlet opening, a pilot valve for said inlet opening, a control diaphragm operatively mounted on said mounting plate and associated with said pilot valve for operating the same, means carried on said mounting plate and yieldingly urging said pilot valve toward closed position, said mounting plate being formed to cooperate with said control diaphragm to afford a control chamber that communicates with said main chamber when said pilot valve is open, means for supplying control pressure to said control chamber, means affording a vent opening for venting pressure fluid from said main chamber, a vent valve for said vent opening, and means operable by said control diaphragm to open said vent valve when said pilot valve is closed, and close said vent valve when said pilot valve is open.

3. In an intake type unloader for compressors and the like, a valve body having a valve chamber and passage therethrough and affording a main valve opening defined within said chamber, a valve member for cooperation with said main valve opening and mounted for reciprocating movement between open and closed positions relative to said main valve opening, a main diaphragm mounted exteriorly of said body in a plane at right angles to the reciprocating path of said main valve member and operatively associated with said valve member for imparting valve closing movement thereto, a mounting plate fixed on said body and cooperating with said main diaphragm to afford a main pressure chamber having a pressure inlet opening, a pilot valve for said inlet opening, a control diaphragm operatively mounted on said mounting plate and associated with said pilot valve for operating the same, means carried on said mounting plate and yieldingly urging said pilot valve toward closed position, said mounting plate being formed to cooperate with said control diaphragm to afford a control chamber that communicates with said main chamber when said pilot valve is open, means for supplying control pressure to said control chamber, said pilot valve having a vent opening formed axially therethrough, and means operated by said control diaphragm to open said vent opening when said pilot valve is closed and to close said vent when said pilot valve is open.

4. In an intake type unloader for compressors and the like, a valve body having a passage therethrough and affording a main valve opening defined in said passage, a valve member for cooperation with said main valve opening and mounted for movement between open and closed positions relative to said main valve opening, a main pressure fluid operated means operatively associated with said valve member for imparting valve closing movement thereto, a pilot valve for controlling the supply of pressure fluid to said main pressure fluid operated means, a second pressure fluid operated means operatively associated with said pilot valve for operating the same, means yieldingly urging said pilot valve toward closed position, means for supplying control pressure to said second fluid pressure operated means, said pilot valve having an axial opening therethrough to afford a vent opening for venting pressure fluid from said main pressure fluid operated means, a vent valve for said vent opening, and means mounted on and operable by said second pressure fluid operated means to open said vent valve when said pilot

valve is closed, and close said vent valve when said pilot valve is open.

5. In an intake type unloader for compressors and the like, a valve body having a passage therethrough and affording a main valve opening defined in said passage, a valve member for cooperation with said main valve opening and mounted for movement between open and closed positions relative to said main valve opening, a main pressure fluid operated means operatively associated with said valve member for imparting valve closing movement thereto, a pilot valve for controlling the supply of pressure fluid to said main pressure fluid operated means, a second pressure fluid operated means operatively associated with said pilot valve for operating the same, means yieldingly urging said pilot valve toward closed position, means for supplying control pressure to said second fluid pressure operated means, means affording a vent opening for venting pressure fluid from said main pressure fluid operated means, a vent valve element for said vent opening, means affording a valve seat element about said vent opening, and means supporting said elements in fixed and relatively movable positions respectively on said second pressure fluid operated means so that said second pressure fluid operated means is operable to open said vent valve when said pilot valve is closed, and is operable to close said vent valve when said pilot valve is open.

6. In an intake type unloader for compressors and the like, a valve body having a passage therethrough and affording a main valve opening defined in said passage, a valve member for cooperation with said main valve opening and mounted for movement between open and closed positions relative to said main valve opening, a main pressure fluid operated means operatively associated with said valve member for imparting valve closing movement thereto, a pilot valve for controlling the supply of pressure fluid to said main pressure fluid operated means, a second pressure fluid operated means operatively associated with said pilot valve for operating the same, means yieldingly urging said pilot valve toward closed position, means for supplying control pressure to said second pressure operated means, means affording a vent opening for venting pressure fluid from said main pressure fluid operated means, a vent valve for said vent opening, and means operable by said second pressure fluid operated means to open said vent valve when said pilot valve is closed, and close said vent valve when said pilot valve is open.

7. In an intake type unloader for compressors and the like, a housing, a wall extending across said housing and having an opening through the central portion thereof to afford a valve port, a flexible diaphragm mounted in said housing and extending thereacross on one side of said wall, means for feeding working fluid through said housing on the opposite side of said diaphragm from said wall, said means including a valve seat in said housing, and a valve member reciprocably mounted in said housing for movement between open and closed positions relative to said valve seat, a retaining member mounted in said housing on said opposite side of said diaphragm from said wall, a spring mounted on said valve between said retaining member and said diaphragm yieldingly maintaining said valve in abutting engagement with said diaphragm and urging said valve toward said open position, and means mounted on the

11

opposite side of said wall from said diaphragm and in communication with said port for selectively feeding working fluid through said port against said diaphragm to flex said diaphragm toward said valve seat and thereby move said valve member into closed position against the urging of said spring.
